[57] **ABSTRACT**

Liquid fabric softener composition containing a cationic fabric softener and a soap having from 16 to 22 carbon atoms in an aqueous vehicle; and a method of softening which comprises rinsing laundered textiles in an aqueous bath of said composition.

9 Claims, No Drawings

FABRIC SOFTENER COMPOSITION AND METHOD

BACKGROUND OF THE INVENTION

This invention relates to fabric softener compositions and to a method of softening textile materials. More particularly, it relates to fabric softening compositions having resistance to the adverse effects of anionic detergent materials and adapted to use in the repetitious but generally discontinuous laundering process which involves soiling, laundering, rinsing, soiling, etc.

The use of fabric softening compositions in household laundering operations to improve the softness or "hand" of laundered textiles has become a widespread practice. These compositions have for the most part been liquid fabric softener compositions containing in a water vehicle a quaternary ammonium salt component having an affinity for negatively-charged fibers and having at least one long chain alkyl moiety of from 16 to 20 carbon atoms. These compositions have been largely adapted for use in the final rinsing bath of the home laundering process. It has been found that the treatment of textile materials in such manner improves the softness or feel of the treated fabrics, prolongs the useful life of the textile materials and reduces the tendency of the fabrics to accumulate electrical charges.

The quaternary ammonium salts of the prior art softener compositions, being cationic in form, have been considered to be incompatible with anionic species. Thus, the prior art has included numerous references to the adverse effects of anionic materials on quaternary ammonium softeners and to the loss of potential benefits of such softeners. Such references, and attempts to mitigate the effects of anionic compounds on quaternary ammonium softeners can be found, for example, in U.S. Pat. No. 3,003,954 to Brown (Oct. 10, 1961); U.S. Pat. No. 3,178,366 to Du Brow et al. (Apr. 13, 1965); U.S. Pat. No. 3,329,609 to Blomfield (July 4, 1967); and in Canadian Pat. No. 818,419 (July 22, 1969). Inasmuch as the final rinsing bath of an automatic washing machine usually contains traces of anionic materials carried over from a preceding washing step, i.e. the intermediate rinses usually do not remove all of the cleaning or washing agents or water softeners, an incompatibility problem has been recognized. Moreover, the tendency to employ higher levels of detergent active, e.g. anionic surfactant, in no-phosphate detergent compositions has in turn resulted in a greater concentration of anionic material in the rinse than has normally been encountered.

It is an object of this invention to provide compositions useful for imparting softness to fabrics.

It is another object of this invention to provide fabric softener compositions containing quaternary ammonium salts and which are compatible with anionic materials.

Another object of the invention is to provide fabric softener compositions effective to impart softness to fabrics in the presence of anionic compounds encountered in laundry rinsing operations.

These and other objects of the invention will become apparent from the description appearing hereinafter.

SUMMARY OF THE INVENTION

The present invention is based in part upon the discovery that fabrics can be improved in feel by treating the fabrics in an aqueous rinsing bath containing resid-

ual anionic materials and a fabric softener composition comprising a cationic fabric softener compound and a minor amount of a fatty soap of from 16 to 22 carbon atoms. In its composition aspect, the present invention provides an aqueous fabric softener composition consisting essentially of:

- A. from 2 to 15% of a cation-active fabric softening compound having from one to two straight chain organic groups of from 8 to 22 carbon atoms;
- B. from 0.5 to 4.0% of an alkali metal salt of a fatty acid of from 16 to 22 carbon atoms;
- C. from 0 to about 2% of an emulsifier selected from the group consisting of (1) the condensation product of 1 mole of alkylphenol wherein the alkyl chain contains from about 8 to about 18 carbon atoms with from about 1 to about 100 moles of ethylene oxide, (2) the condensation product of 1 mole of an aliphatic alcohol wherein the alkyl chain contains from about 10 to about 24 carbon atoms with from about 1 to about 100 moles of ethylene oxide, (3) polyethylene glycols having a molecular weight of from about 1,400 to about 30,000, and (4) mixtures thereof; and
- D. the balance water.

In its method aspect, the present invention provides a method of imparting softening properties to washed textiles which comprises treating previously-washed textiles in an aqueous rinsing bath containing minor amounts of anionic compounds from said previous washing and an amount effective to soften the fabrics of a composition hereinbefore defined.

The fabric softening compositions of this invention provide softening properties to treated textiles notwithstanding the presence of residual anionic compounds carried over into the rinse from a previous detergent wash. At low levels of softener agent usage, the presence of soap permits an improved level of fabric softening which could be obtained from the same composition free of the soap component or from a composition containing additional softener agent in place of the soap.

DETAILED DESCRIPTION OF THE INVENTION

The cation-active organic fabric-softener compounds, which are the principal fabric-softening components of the compositions of the invention, are known fabric-softening compounds. Generally, these comprise cationic nitrogen-containing compounds such as quaternary ammonium compounds and amines and have one or two straight-chain organic groups of at least eight carbon atoms. Preferably, they have one or two such groups of from 12 to 22 carbon atoms. Preferred cation-active softener compounds include the quaternary ammonium softener compounds corresponding to the formula

wherein R is hydrogen or an aliphatic group of from 12 to 22 carbons; R₁ is an aliphatic group having from 12 to 22 carbon atoms; R₂ and R₃ are each alkyl groups of from 1 to 3 carbon atoms; and X is an anion selected from halogen, acetate phosphate, nitrite and methyl sulfate radicals.

Because of their excellent softening efficacy and ready availability, preferred cationic softener com-

pounds of the invention are the dialkyl dimethyl ammonium chlorides, wherein the alkyl groups have from 12 to 22 carbon atoms and are derived from long-chain fatty acids, such as hydrogenated tallow. As employed herein, alkyl is intended as including unsaturated compounds such as are present in alkyl groups derived from naturally occurring fatty oils. The term "tallow" refers to fatty alkyl groups derived from tallow fatty acids. Such fatty acids give rise to quaternary softener compounds wherein R and R₁ have predominantly from 16 to 18 carbon atoms. The term "coconut" refers to fatty acid groups from coconut oil fatty acids. The coconut-alkyl R and R₁ groups have from about 8 to about 18 carbon atoms and predominate in C₁₂ to C₁₄ alkyl groups. Representative examples of quaternary softeners of the invention include tallow trimethyl ammonium chloride; ditallow dimethyl ammonium chloride; ditallow dimethyl ammonium methyl sulfate; dihexadecyl dimethyl ammonium chloride; di(hydrogenated tallow) dimethyl ammonium chloride; dioctadecyl dimethyl ammonium chloride; dieicosyl dimethyl ammonium chloride; didocosyl dimethyl ammonium chloride; di(hydrogenated tallow) dimethyl ammonium methyl sulfate; dihexadecyl diethyl ammonium chloride; dihexadecyl dimethyl ammonium acetate; ditallow dipropyl ammonium phosphate; ditallow dimethyl ammonium nitrite; di(coconutalkyl) dimethyl ammonium chloride.

An especially preferred class of quaternary ammonium softeners of the invention correspond to the formula

wherein R and R₁ are each straight chain aliphatic groups of from 12 to 22 carbon atoms and X is halogen, e.g., chloride. Especially preferred are ditallow dimethyl ammonium chloride and di(hydrogenated tallow-alkyl) dimethyl ammonium chloride and di(coconut-alkyl) dimethyl ammonium chloride, these compounds being preferred from the standpoint of excellent softening properties and ready availability.

Suitable cation-active amine softener compounds are the primary, secondary and tertiary amine compounds having at least one straight-chain organic group of from 12 to 22 carbon atoms and 1,3-propylene diamine compounds having a straight-chain organic group of from 12 to 22 carbon atoms. Examples of such softener actives include primary tallow amine; primary hydrogenated-tallow amine; tallow 1,3-propylene diamine; oleyl 1,3-propylene diamine; coconut 1,3-propylene diamine; soya 1,3-propylene diamine and the like.

Other suitable cation-active softener compounds herein are the quaternary imidazolinium salts. Preferred salts are those conforming to the formula

wherein R₆ is an alkyl containing from 1 to 4, preferably from 1 to 2, carbon atoms, R₇ is an alkyl containing from 1 to 4 carbon atoms or a hydrogen radical, R₈ is an alkyl containing from 8 to 22, preferably at least 15, carbon atoms, R₅ is hydrogen or an alkyl containing from 8 to 22, preferably at least 15, carbon atoms, and X is an anion, preferably methyl sulfate or chloride ions. Other suitable anions include those disclosed with reference to the cationic quaternary ammonium fabric softeners described hereinbefore. Particularly preferred are those imidazolinium compounds in which both R₅ and R₈ are alkyls of from 12 to 22 carbon atoms, e.g., 2-heptadecyl-1,1-methyl [(2-stearoylamido)ethyl] imidazolinium methyl sulfate.

Other cationic quaternary ammonium fabric softeners, which are useful herein include, for example, alkyl (C₁₂ to C₂₂)-pyridinium chlorides, alkyl (C₁₂ to C₂₂)-alkyl (C₁ to C₃)-morpholinium chlorides, and quaternary derivatives of amino acids and amino esters.

The cationic fabric softeners mentioned above can be used singly or in combination in the practice of the present invention. The cationic fabric softener comprises from about 2 to about 15% by weight of the total composition. If more than about 15% is used, product stability problems may occur, e.g., thickening and the possible formation of an undesired gel and if less than about 2% is used, the softener will be too dilute and desired softening of the fabrics will not be achieved when conventional amounts of the composition are added to the wash water. Within the above range, the actual amount of fabric softener which is contained in the composition depends upon the desired usage concentration of the composition in a laundering process. A desired concentration of the fabric softener in the washing solution is from about 25 ppm to about 100 ppm. To achieve the desired results of the present invention the preferred range of cationic fabric softener is from about 2.5% to about 6% by weight of the total composition.

The alkali metal soap component suitable for use in the compositions of the present invention include the sodium and potassium soaps of higher fatty acids of from 16 to 22 carbon atoms or mixtures thereof. These soaps can be incorporated into an aqueous cationic fabric softening composition with the provision of a composition which still effectively softens fabrics in a laundry rinsing cycle containing residual anionics. Whereas such soaps can be compatibly combined with cationic softeners, soaps of fatty acids having less than 16 carbon atoms tend to mitigate the fabric-softening effects of the cationic softener.

Commercial soaps are generally based upon mixtures of fatty acid compounds obtained from natural sources such as tallow, coconut oil, palm kernel oil or babassu kernel oil; other commercial soaps are synthetically manufactured to simulate the fatty acids from natural materials such as tallow. Soaps from any of these commercial sources can be suitably employed so long as they contain or are altered or modified to contain at least 50%, and preferably at least 80%, by weight of fatty acids having from 16 to 22 carbon atoms. Thus, tallow soaps which include the sodium or potassium salts of the mixtures of fatty acids derived from tallow can be suitably employed. Tallow soaps predominate in C₁₆/C₁₈ fractions and can be suitably employed in a cationic-containing fabric-softening composition. In contrast, coconut soaps, which predominate in C₁₂/C₁₄ fractions, mitigate the softening effects, for example, of

quaternary ammonium softener and are not suitable herein. It will be appreciated that fatty acid soaps derived from mixtures of natural fatty acid sources can be employed, where desired, so long as the resulting soap mixtures predominate in soaps of C_{16} or higher fatty acids as described hereinbefore. A preferred soap mixture is a tallow/coconut soap blend of proportion 90:10. This mixture is preferred from the standpoints of providing desirably optimum performance and aesthetic characteristics.

The term tallow as used herein refers to a mixture of soaps having an approximate chain-length distribution of: 2% C_{14} ; 32% C_{16} ; and 66% C_{18} .

The term coconut as used herein in connection with soap or free fatty acid mixtures refers to materials having an approximate carbon chain length distribution of: 8% C_8 ; 7% C_{10} ; 48% C_{12} ; 17% C_{14} ; 9% C_{16} ; 11% C_{18} .

The amount of alkali metal soap employed to provide effective resistance of the softener to the adverse effects of anionic substances will depend on such factors as the particular softening agent employed, the kind of soap, the nature of the anionic substance and the desired viscosity or physical appearance. As little as 0.5% of the soap based on the weight of composition may be enough in some instance, whereas up to about 4% of the soap may be required in others. The relative proportions of the cation-active fabric softener compound and soap will be based more on physical stability considerations than on performance considerations. While amounts of fabric softener and soap components within the ranges hereinbefore defined will permit the preparation of softening compositions having resistance to the residual anionics in a rinsing operation, certain ratios will be preferred to assure that the hydrophilic/lipophilic balance allows for the provision of a composition of stable physical form. Thus, compositions containing, for example, distearyl dimethyl ammonium chloride and alkali metal 90/10 tallow/coconut soaps, respectively, in relative weight proportions of about 1:1 or about 5:1 are preferred. These compositions are uniform in appearance and do not separate into discrete phases. Fabric softening effects are observed notwithstanding the admixture of both cationic and anionic substances. The percentages of fabric softener and soap may be adjusted within the above defined limits to suit the requirements of each case and to combine softening and stability effects.

The compositions of the invention can be formulated in a convenient manner by admixture of the softener and soap components and addition to water. A preferred method of preparing the compositions involves the preparation of an aqueous soap solution and addition to an aqueous dispersion of the softening agent. It has been found that the admixture of aqueous solutions of softening agent and soap permits the preparation of a uniform, homogeneous composition having a pleasing pearlescent appearance. The composition is free of undesirable greasy or flocculent precipitate. While applicant does not wish to be bound by any precise theory as to the mechanism by which a uniform and homogeneous composition is obtained in contrast to the greasy flocculent precipitate expected from the prior art teachings regarding cationic/anionic interactions, it is believed that a water-soluble or dispersible complex or mixed micelle may be formed when the anionic substance is a higher fatty soap as hereinbefore described.

It has been discovered that the presence of soap in the compositions of the invention, rather than having

an opposing or counteractive effect on the fabric substantive softening agent, can contribute actively to the softening function at low level usage of the complete composition. Thus, an aqueous composition of the invention containing 2.5% ditallow dimethyl quaternary ammonium chloride and 2.5% of sodium 90/10 tallow/coconut soap and added to the final rinse of an automatic washing machine in an amount of one fluid ounce provides a higher level of softening performance than is obtained where one fluid ounce of fabric softener having 5% of the quaternary compound is employed. The same softening contribution is not observed with higher usage levels, e.g. two fluid ounces, in which case the compositions of the invention will have their greater attraction to users who customarily or habitually employ low levels of softening composition in laundering operations. The compositions of the invention are additionally characterized by a pearlescent appearance which may be attractive to users of fabric softening compositions.

The compositions of the invention will preferably contain an emulsifying agent. Suitable emulsifiers which can be utilized in the compositions of the present invention include those selected from the group consisting of (1) the condensation product of 1 mole of alkylphenol wherein the alkyl chain contains from about 8 to about 18 carbon atoms with from about 1 to about 100 moles of ethylene oxide. Specific examples of these nonionics are the condensation product of 1 mole of nonylphenol with 9.5 moles of ethylene oxide; the condensation product of 1 mole of decylphenol with 40 moles of ethylene oxide; the condensation product of 1 mole of dodecylphenol with 35 moles of ethylene oxide; the condensation product of 1 mole of nonylphenol with 1.5 moles of ethylene oxide; the condensation product of 1 mole of tetradecylphenol with 35 moles of ethylene oxide; and the condensation product of 1 mole of hexadecylphenol with 30 moles of ethylene oxide; (2) the condensation product of 1 mole of an aliphatic alcohol wherein the alkyl chain contains from 10 to about 24 carbon atoms with from about 1 to about 100 moles of ethylene oxide. Specific examples are the condensation product of 1 mole of coconut alkyl alcohol with 45 moles of ethylene oxide; the condensation product of 1 mole of tallow-alkyl alcohol with 30 moles of ethylene oxide; the product sold by Union Carbide under the tradename "Tergitol 15-S-9" which is the condensation product of 1 mole of secondary alkyl alcohol with alkyl chain lengths of from 11 to 15 with 9 moles of ethylene oxide; and the product sold by Union Carbide under the tradename "Tergitol 15-S-3" which is the condensation product of 1 mole of secondary alkyl alcohol with alkyl chain lengths of from 11 to 15 with 3 moles of ethylene oxide; (3) polyethylene glycols having a molecular weight of from about 1,400 to about 30,000. For example, Dow Chemical Company manufactures these nonionics in molecular weights of 20,000, 9,500, 7,500, 4,500, 3,400 and 1,450. All of these nonionics are wax-like solids which melt between 100° and 200°F, and (4) mixtures thereof.

These emulsifiers function as solubilizing agents to prevent precipitation and maintain excellent freeze-thaw characteristics of the liquid compositions. These emulsifiers further act as stabilizers to promote shelf stability and maintain the desired viscosity. The emulsifiers are present in the composition of the present invention from about 0 to about 2% by weight, preferably from about 0.25% to about 1%. If more than about 2%

by weight is used no advantages are achieved and product stability problems can arise. Small amounts of emulsifier are usually necessary to achieve the desired stability and freeze-thaw characteristics while maintaining the desired viscosity of the composition.

Miscellaneous materials such as optical brighteners such as the anionic stilbenes, coloring agents, perfumes, and other materials which are well known as constituents in fabric softener compositions and which are compatible in the compositions of the present invention can also be present in minor amounts.

The following examples illustrate the manner in which the present invention can be practiced. However, the invention is not confined to the specific limitations set forth in the examples, but rather, to the scope of the appended claims.

EXAMPLE I

A soap solution was prepared by dissolving 50 g. of a commercially-available laundry soap composition into 1,000 ml. of soft water at 170°F. The resulting solution contained the following approximate composition in parts by weight:

Component	Parts by Weight
Sodium tallow soap	3.2
Potassium tallow soap	0.82
Sodium coconut soap	0.36
Potassium coconut soap	0.09
Optical Brightener, perfume, and miscellaneous	0.05
Water	Balance to 100

To the warm soap solution prepared as described were added with gentle stirring 1,000 ml. of a commercially available aqueous fabric softening composition having the following approximate composition:

Component	Parts by Weight
Ditallow Dimethyl Ammonium Chloride	5.2
Emulsifier (mixture of nonyl-phenol ethoxylates)	0.5
Isopropanol, optical brightener, dye, perfume, miscellaneous	1.3
Water	Balance to 100

The resulting soap/softener composition had the following approximate composition:

Component	Parts by Weight
Ditallow Dimethyl Ammonium Chloride	2.6
Soap (90/10 tallow/coconut)	2.3
Emulsifier	0.3
Isopropanol, ethanol, optical brightener, dye, perfume, and miscellaneous	0.7
Water	Balance to 100

The composition was characterized by a pearlescent appearance upon cooling and was physically stable, i.e. did not separate upon standing.

The composition of Example I was used as follows: Five terry wash cloths were washed in a miniature-size,

top loading washing machine containing 1½ gals. of water having a temperature of 130°F, and a hardness of 7 grains, using 6.1 grams of a commercially-available anionic-based laundry detergent. The washing process lasted ten minutes. The cloths were then rinsed using 1½ gals. of 100°F. water and 2.6 cc. or 5.2 cc. of the composition of Example I (corresponding, respectively, to 1 or 2 fluid ounces in 17 gal. of water). This cycle of washing and rinsing was then repeated. The composition of Example I gave noticeable softening effects at levels of 1 and 2 ounces on the terry wash cloths. Whereas, the commercially-available softener composition described hereinbefore provided a greater softening effect at the two-ounce level than the composition of Example I, the composition of Example I provided a greater effect at the 1 ounce level.

Substantially the same results in softening are obtained with the composition of Example I when any of the following cationic fabric softeners is substituted on an equal weight basis for the ditallow dimethyl ammonium chloride in Example I, (coconut as used below has the following chain length distribution: 2% C₁₀, 66% C₁₂, 23% C₁₄, and 9% C₁₆):

ditallowalkyl dimethyl ammonium chloride,
dioctadecyl dimethyl ammonium chloride,
tallowalkyl dimethyl (3-tallowalkoxy-2-hydroxypropyl) ammonium chloride,
2-heptadecyl-1-methyl-1-[(2-stearoylamino)ethyl]imidazolonium methyl sulfate,
eicosyl dimethyl benzyl ammonium chloride,
eicosyl trimethyl ammonium chloride,
tetradecyl-tri-(2-hydroxyethyl)ammonium methyl sulfate,
octadecyl-tri-(2-hydroxyethyl)ammonium methyl sulfate,
di(2-benzyl octadecyl)dimethyl ammonium ethyl sulfate,
di(3-oxa-heptadecyl) di(3-hydroxypropyl) ammonium bromide,
di(2-dodecoxyethyl)dimethyl ammonium chloride,
di(2-stearoyloxyethyl)dimethyl ammonium chloride,
2-stearoyloxyethyl triethyl ammonium chloride,
di(4-hydroxyoctadecyl)dimethyl ammonium ethyl sulfate,
2,4-dihydroxyoctadecyl trimethyl ammonium chloride,
di(2-stearamidopropyl) dimethyl ammonium chloride,
ditallowalkyl dimethyl ammonium bromide,
ditallowalkyl dimethyl ammonium methyl sulfate,
ditetradecyl diethyl ammonium chloride,
ditetradecyl dimethyl ammonium chloride,
coconutalkyl triethyl ammonium chloride, and
dicoconutalkyl diethyl ammonium chloride.

Substantially the same results in softening are obtained with the compositions of Example I when any of the following emulsifiers are substituted on an equal weight basis for the nonyl phenol ethoxylate of Example I. (coconut as used below has the following chain length distribution: 2% C₁₀, 66% C₁₂, 23% C₁₄, and 9% C₁₆).

The condensation product of 1 mole of decylphenol with 40 moles of ethylene oxide; the condensation product of 1 mole of dodecylphenol with 35 moles of ethylene oxide; the condensation product of 1 mole of tetradecylphenol with 35 moles of ethylene oxide; the condensation product of 1 mole of heptadecylphenol

with 30 moles of ethylene oxide; the condensation product of coconut-alkyl alcohol with 45 moles of ethylene oxide; the condensation product of tallow-alkyl alcohol with 30 moles of ethylene oxide; the condensation product of 1 mole of secondary alkyl alcohol with 9 moles of ethylene oxide, the alkyl group containing alkyl chain lengths from 11 to 15 (Tergitol 15-S-9); the condensation product of 1 mole secondary alkyl alcohol with 3 moles of ethylene oxide, the alkyl group containing alkyl chain lengths from 11 to 15 (Tergitol 15-S-3); polyethylene glycol having a molecular weight of 20,000; polyethylene glycol having a molecular weight of 9,500; polyethylene glycol having a molecular weight of 7,500; polyethylene glycol having a molecular weight of 4,500; polyethylene glycol having a molecular weight of 3,400; polyethylene glycol having a molecular weight of 1,450; and mixtures thereof.

EXAMPLE II

A fabric softener composition was prepared according to the procedure of Example I containing the following ingredients:

Component	Parts by Weight
Distearyl dimethyl ammonium chloride	5.2
Sodium and potassium tallow soap	0.9
Sodium and potassium coconut soap	0.1
Ethoxylated nonylphenols of Example I	0.3
Isopropanol, ethanol, optical brighteners, dye, perfume, miscellaneous	1.6
Water	Balance to 100

The fabric softener composition thus formulated was stable. When tested according to the procedure of Example I, the clothes utilized were soft to the touch.

EXAMPLE III

A fabric softener composition is prepared according to the procedure of Example I and contains the following ingredients:

Component	Parts by Weight
Distearyl dimethyl ammonium chloride	5.5
Sodium and potassium tallow soap	1.0
Sodium and potassium coconut soap	0.1
Emulsifier (mixture of secondary C ₁₁₋₁₅ alcohol ethoxylates)	0.4
Isopropanol, ethanol, optical brighteners, dye, perfume, miscellaneous	1.6
Water	Balance to 100

In addition to the preferred embodiments described herein, other arrangements and variations within the spirit and scope of the present invention and the appended claims will occur to those skilled in the art.

What is claimed is:

1. A liquid softener composition consisting essentially of

A. from about 2 to about 15% by weight of a cationactive fabric softener compound having two straight-chain organic groups of from 8 to 22 carbon atoms;

B. from about 0.5 to about 4% of an alkali metal salt of a fatty acid of from 16 to 22 carbon atoms or a mixture of fatty acid soaps, at least 50% of said mixture having 16 or more carbon atoms;

C. from 0 to about 2% of an emulsifier selected from the group consisting of

1. the condensation product of 1 mole of alkylphenol wherein the alkyl chain contains from about 8 to about 18 carbon atoms with from about 1 to about 100 moles of ethylene oxide;

2. the condensation product of 1 mole of an aliphatic alcohol wherein the alkyl chain contains from about 10 to about 24 carbon atoms with from about 1 to about 100 moles of ethylene oxide;

3. polyethylene glycol having a molecular weight of from about 1400 to about 30,000;

4. mixtures thereof; and

D. the balance water.

2. The composition of claim 1 wherein the cationactive fabric softener compound is a quaternary ammonium softener compound having the formula

wherein R is an aliphatic group of from 12 to 22 carbons; R₁ is an aliphatic group having from 12 to 22 carbon atoms; R₂ and R₃ are each alkyl groups of from 1 to 3 carbon atoms; and X is an anion selected from the group consisting of halogen, acetate, phosphate, nitrite and methylsulfate.

3. The composition of claim 2 wherein R and R₁ are each stearyl, R₂ and R₃ are each methyl and X is chloride.

4. The composition of claim 1 wherein the soap is a mixture of alkali metal soaps, at least 50% of such soaps having from 16 to 22 carbon atoms.

5. The composition of claim 1 wherein the soap is a mixture of alkali metal tallow and coconut soaps, the ratio of tallow to coconut soaps being from 95:5 to 50:50.

6. The composition of claim 1 wherein the soap is tallow soap.

7. The composition of claim 1 wherein the emulsifier ranges from 0.25% to 1% and is a mixture of nonylphenol ethoxylates.

8. The composition of claim 5 wherein the emulsifier ranges from 0.25% to 1% and is a mixture of secondary C₁₁₋₁₅ alcohol ethoxylates.

9. The composition of claim 1 wherein the cationic fabric softener ranges from 2.5% to about 6%.
